UNITED STATES PATENT OFFICE.

AMOS P. STEINER, OF WAYNESBORO, PENNSYLVANIA, ASSIGNOR TO LANDIS TOOL COMPANY, OF WAYNESBORO, PENNSYLVANIA, A CORPORATION OF PENNSYLVANIA. SIZING DEVICE FOR INTERNAL-GRINDING MACHINES.

Application filed October 21, 1926. Serial No. 143,249.

My invention relates to an automatic work-sizing device for grinding machines. Heretofore it has been necessary for the operator to remove the grinding wheel from the work and measure the ground surface with a gage or calipers to ascertain the degree of the grinding. The main object of this device is to automatically indicate exactly when the grinding has reached the proper point. Another object is to control the feed or advance of the indicating device hydraulically and the retraction thereof by means of a strong spring. A further object is to provide a feeler arm which bears against the surface being ground, and connections from the feeler arm to an indicator. A further object is to control the position of the feeler arm and indicator operating arm by the movement of the wheel carrying.

Referring to the accompanying drawings which are made a part hereof and in which like numerals represent similar parts in the views of which,

Figure 1 is a plan view of the sizing device and a portion of the machine upon which it is mounted,

Figure 2, a front elevation of the device partly in section, and

Figure 3, a section on the line 3—3 of Figure 2.

In the drawings, the numeral 10 denotes the base of a ball-race grinder, 11 the wheel carriage, 12 the grinding wheel, 13 the head stock and 14 the work, which is securely held against a chuck 15 by means of the collar 16. Surrounding the chuck 15 is a casting 16' forming a water-guard and also a support for the sizing device.

The sizing device comprises a casting 17 having a horizontally disposed pressure cylinder 18 positioned at an angle with respect to the axis of the work and a vertically disposed shaft housing 19, the axis of the cylinder 18 being tangent to the cylinder housing 19. The casting 17 is secured to the water guard 16' by means of a T-headed bolt 20 carried by said casting with its head hitting into a slot 21 formed in the water guard. A piston 22 having an extension 23 is adapted to operate in the cylinder 18 and is carried on the end of a rod 24 which passes through a stuffing box 25 secured to the open end of the cylinder. A spring 26

is confined between the piston and the stuffing box to force the piston towards the closed end of the cylinder. The opposite end of the rod 24 carries a rack 27 which operates within a housing 28 bolted to the top of the housing 19 and which meshes with a pinion 29 loosely mounted on a spindle 30 provided with ball bearings 31 to insure easy operation. A collar 32 is secured to the spindle 30 by a set screw 33 and carries a small pin 34 projecting from its side and engaging in a relatively large slot 35 in the pinion 29. The pin 34 provides driving connection between the pinion and the collar 32. Since the pin is much smaller than the slot in which it fits, a lost motion is permitted between the pinion and collar to eliminate any sudden jarring of the parts.

On the end of the spindle 30 adjacent the pinion 29 is an indicator arm 36, the free end of which rests against a plunger 37 of an indicator 38 designed to indicate to the operator, the exact condition of the work being done. The spindle 30 is normally held under tension in one direction by a spring 39 which encircles the spindle and has one end anchored in a collar 40 held by a pin 41 to the housing 19 and its other end anchored in a nut 42 threaded on the spindle 30 and confined thereon by a similar lock nut 43. A feeler-arm 44 is pinned to the end of the spindle opposite the indicator arm 36 and is adapted to rest against the surface on the work which is being ground.

The cylinder 18 has an inlet port 45' communicating with a pressure pipe 45 between the end of the cylinder and the piston 22 and a cylinder drain port 46' communicating with a drain pipe 46 which is designed to carry off any fluid which may leak past the piston and into the cylinder.

The feeler arm 44 and indicator arm 36 being both keyed to the spindle, work in unison and are controlled entirely by the piston 22 which is designed to cause the entire sizing device to enter the position in 100 the work slowly and leave it rapidly by the following operation:

When a piece of work 14 has been ground to size, the grinding wheel 12 is withdrawn. When the wheel carriage reaches the limit 105 to which it may be withdrawn, a dog 47 (Fig. 1) strikes the head on a valve stem 48 of a valve 49, normally held closed by a

spring 50, opening the valve and allowing fluid under pressure to pass from a supply pipe 51 through the pressure line 52 to a T connection 53 where the line divides, one 5 division leading to a needle valve 54 and the other to a check-valve 55. Both valves then connect to another T connection 56 to the pipe 45 leading to the cylinder 18. When the pressure fluid is moving towards the 10 cylinder 18, it follows the path of least resistances, which is through the check-valve 55 since the needle valve is always kept sufficiently closed to provide a very restricted passage therethrough. Said pressure fluid 15 enters the cylinder 18 and acts against the piston 22 which in turn moves the rack 27 and pinion 29 in such a direction as to turn the spindle 30 carrying the feeler arm 44 away from the work and the indicator arm 20 36 away from the indicator so that the work may be removed from the chuck.

When a new piece of work is placed in the chuck, and the grinding wheel is moved towards the work, the dog 47 releases the 25 valve stem 48 which is returned to its normal or exhaust position by the spring 50. With the valve-piston in this position, the pressure fluid is forced out of the cylinder 18 by the action of the spring 26 against the piston 22. 30 The pressure fluid cannot return through the check-valve 55 so it escapes through the needle-valve 54 which is adjusted to allow the parts to move slowly thereby allowing the feeler-arm 44 to engage the work 14 35 slightly ahead of the grinding wheel 12 thereby preventing any damage to the indicator by the indicator arm 44 engaging therewith. The pressure fluid which is exhausted from the cylinder 18 by the pressure 40 of the spring 26 passes through the pipe 45 to the valve 49 then returns to the storage tank through the pipe 57.

It will be obvious to those skilled in the art, that various changes may be made in 45 my device without departing from the spirit of my invention and therefore I do not limit myself to what is shown in the drawings and described in the specification but only as indicated in the appended claims.

50 Having thus described my said invention, what I claim as new and desire to secure by Letters Patent, is:

1. The combination with a grinding machine having a work holding chuck, of a water guard around said chuck and a hydraulic sizing device carried by said water guard and means controlled by the movement of the grinding machine carriage for moving the sizing device into and out of operative 55 position, substantially as set forth.

2. The combination with a grinding machine having a work holding chuck, of a water guard around said chuck, said water guard having a T slot formed therein, a hydraulic sizing device carried by said water 60

guard and a bolt carried by said sizing device and engaging said slot to secure the two together, substantially as set forth.

3. The combination with an internal grinding machine having a work-holding 70 chuck and a water guard around said chuck, of a sizing device comprising a feeler arm for engaging the work, an indicating arm for engaging an indicator, means for engaging said arms against said work and indicator and separate means for disengaging said arms therefrom, substantially as set forth.

4. The combination with an internal grinding machine having a work-holding 80 chuck and a water-guard surrounding said chuck, of a sizing device secured to said water-guard and comprising a feeler arm for engaging the work, an indicator, an arm for engaging said indicator, mechanical 85 means for engaging said arms with said work and indicator and hydraulic means for disengaging said arm therefrom, substantially as set forth.

5. The combination with an internal 90 grinding machine having a work-holding chuck and a water guard, of a sizing device carried by said water guard and comprising a casting having a vertical cylindrical housing, a spindle journaled in said housing, 95 an indicator, an arm to operate said indicator on one end of said spindle, a work engaging feeler arm on the opposite end of said spindle and tension means to hold said arms against said indicator and work, substantially as set forth.

6. A work sizing device for internal grinders comprising a casting, an indicator on said casting, a vertical housing in said casting, a spindle in said housing, an indicator engaging arm on said spindle, a work 105 engaging arm on said spindle, a collar surrounding said spindle and secured to said housing, a collar secured to said spindle, a spring under tension connecting said collars 110 to hold said arms into their respective engagement and hydraulic means for disengaging said arms, substantially as set forth.

7. A work sizing device for internal grinders comprising a casting, an indicator on said casting, a vertical housing in said casting, a spindle journaled in said housing, an indicator engaging arm and work 115 engaging arm on said spindle, a pinion loosely mounted on said spindle, a collar 120 keyed to said spindle adjacent said pinion, a slot in said pinion, a pin on said collar engaging said slot and hydraulic means to rotate said pinion and spindle, substantially as set forth.

8. A work sizing device for internal grinders comprising a casting, an indicator on said casting, a vertical housing in said casting, a spindle journaled in said housing, an indicator engaging arm and work engag- 130

- ng arm on said spindle, pinion driving means on said spindle, a horizontal cylinder in said casting, a piston and piston rod in said cylinder, a rack on said piston rod engaging 5 said pinion, mechanical means for forcing said piston in one direction, pressure fluid means for forcing said piston in the opposite direction and means to control said pressure fluid, substantially as set forth.
- 10 9. The combination of an internal grinding machine having a base, a reciprocating wheel carriage on said base, a work holding chuck and a water guard, of a work sizing device comprising a casting, a spindle jour- 15 nalled in said casting, an indicator, an indicator engaging arm and a work engaging arm on said spindle, a fluid cylinder in said casting, a piston and piston rod in said cylinder, a rack on said piston rod engaging 20 a pinion on said spindle, a fluid supply line for said cylinder and means on said wheel carriage to control the flow of fluid to said cylinder, substantially as set forth.
10. The combination of an internal 25 grinding machine having a base, a reciprocating wheel carriage on said base, a work holding chuck and a water guard, of a work sizing device, a fluid pressure cylinder for operating said device, a fluid supply line, a two-way valve in said line, a check-valve 30 in said line, a by-pass around said check-valve, a needle-valve in said by-pass, a fluid line from said two-way valve and an arm on said wheel-carriage to operate said two-way valve, substantially as set forth.

In witness whereof, I have hereunto set my hand at Waynesboro, Pennsylvania, this 18th day of October, A. D. nineteen hundred and twenty-six.

AMOS P. STEINER.
